TOWEL CABINET

Leo M. Harvey, Los Angeles, Calif.

Application January 24, 1938, Serial No. 186,645

9 Claims. (Cl. 312—55)

This invention relates to dispensing devices and relates more particularly to devices for dispensing paper towels and the like. A general object of this invention is to provide a convenient, inexpensive and practical towel cabinet.

Another object of this invention is to provide a towel cabinet for handling paper towels having folded corner portions that operates to project the folded-over corner portions from the case to be conveniently grasped by the user.

It has been found that the users of paper towel cabinets often have difficulty in withdrawing the towels from the cabinets. The hands of a user of a towel cabinet are usually wet and when the accessible parts of a paper towel are grasped to withdraw a towel from the cabinet the moisture is immediately transferred to the absorbent paper. The moisture softens the towel so that the towel parts or tears and the user of the cabinet is obliged to re-engage the towel or to reoperate the ejecting mechanism or both. The towel cabinet of the present invention overcomes this difficulty and is operable to eject doubled or folded portions of the towel of two thicknesses of paper that are sufficiently strong to withstand the pull exerted by the user of the cabinet even though his hands may be wet.

Another object of this invention is to provide a towel cabinet of the character mentioned that ejects the folded or doubled corner portions of the paper towels in such a manner that the users may grasp them at their strongest parts adjacent their lines of folding.

Another object of this invention is to provide a towel cabinet of the character mentioned that embodies a positive dependable means for ejecting the towels to positions where their doubled or folded portions are conveniently accessible to the user.

Another object of this invention is to provide a towel cabinet of the character mentioned in which the ejecting mechanism acts on the folded corner portions of a towel to bodily advance or move the towel to make said folded corner portions conveniently accessible for grasping.

Another object of this invention is to provide a towel cabinet of the character mentioned embodying a novel and particularly effective ejecting mechanism that operates to move the lowermost towel forwardly and then downwardly to project its folded corner portions and performs this function without crushing, wrinkling or disturbing the other towels of the stack.

Another object of this invention is to provide a towel cabinet of the character mentioned em-

bodying a simple yet effective means for unfolding the inner or rear fold of the lowermost towel as the same is being withdrawn from the case.

Another object of this invention is to provide a towel cabinet of the character mentioned in which the stack of towels is related to the discharge opening in such a manner that it is difficult if not impossible, to obtain or even engage the towels within the case.

A further object of this invention is to provide a towel cabinet of the character mentioned that embodies a minimum number of simple parts and that is inexpensive to manufacture.

The various objects and features of my invention will be fully understood from the following detailed description of a typical preferred form and application of my invention, throughout which description reference is made to the accompanying drawings, in which:

Fig. 1 is a front view of the towel cabinet of the present invention. Fig. 2 is a side view of the towel cabinet. Fig. 3 is an enlarged horizontal detailed sectional view taken as indicated by line 3—3 on Fig. 1 showing the ejecting means in its normal condition. Figs. 4 and 5 are fragmentary vertical detailed sectional views of the lower portion of the case, being views taken as indicated by lines 4—4 and 5—5 respectively, on Fig. 3. Fig. 6 is a view similar to Fig. 5 showing parts of the ejecting means in the operated positions where the lowermost towel is projected from the case. Fig. 7 is a horizontal detailed sectional view taken as indicated by line 7—7 on Fig. 6. Fig. 8 is a slightly reduced bottom elevation of one of the towels and Fig. 9 is a vertical sectional view taken as indicated by line 9—9 on Fig. 8.

The present invention may be embodied in devices for handling paper towels, napkins, toilet paper, cleaning tissues and the like. In the following detailed disclosures I will describe a typical preferred form of the invention for handling paper towels. It is to be understood that the invention is not to be construed as limited or restricted to the particular form or application of the invention about to be described.

The towel cabinet of the present invention includes, generally, a cabinet or case 10 for containing a stack of towels T, ejecting means 11 for acting on the towels T to eject portions of the same from the case 10 and means 12 for operating the ejecting means 11.

The case 10 may be varied in proportion, construction, etc., to handle paper products of various kinds and shapes. The housing or case 10 may be formed of sheet metal or the like and is

adapted to be secured to a wall or other vertical support. The case 10 includes a vertical back 12a, vertical sides 13, a substantially horizontal bottom 14 and a substantially horizontal top 15. 5 The bottom 14 may be secured to in-turned flanges 16 on the back 12a and sides 13.

The case 10 is shaped to receive a stack of the folded towels T. In accordance with the invention the case 10 has a horizontal cross sectional 10 shape corresponding to the plan configuration of the towel T to conform to the contained stack of towels. The case sides 13 are parallel and at right angles to the back 12a. The case 10 includes a front F shaped to conform to the forward portions of the folded towels T and shaped to provide the case 10 with three walls or sides. The front F has a central wall portion 17 that is substantially vertical and parallel with the back 12a and two wall portions 18 diverging rearwardly and laterally from the central wall portion 17. The divergent wall portions 18 are substantially vertical and extend rearwardly and laterally from the central wall portion 17 to the planes of the case sides 13. Rims or flanges 19 20 are provided on the wall portions 18 to overlap the forward portions of the case sides 13 and to lie parallel with the same. The flanges 19 may be engageable with beads 20 on the sides 13 to limit the inward movement of the front F. The 25 forward parts of the case sides 13 may be bevelled upwardly and inwardly and the upper parts of the several wall portions 17 and 18 of the front F may be bevelled in a similar manner, if desired. A mirror 21a may be provided on the 30 central wall portion 17 of the case front F.

The front F forms a closure for the case 10 and is hinged or pivoted to the case so that it may be lowered or opened to render the interior of the case readily accessible. The above described flanges 19 project downwardly beyond the lower ends of the wall portions 18 and pivot pins 21 are arranged through openings in the case sides 13 and the depending parts of the flanges 19 to pivotally connect the front F with the case 10. The front F is adapted to be lowered from the closed position illustrated in the drawings to an open position where the interior of the case 10 is fully accessible so that a stack of towels T may be readily passed into the case. 50 A latch or lock 23 may be provided to normally retain the front F in its closed position.

A support or shelf 22 is provided in the case 10 to assist in supporting the stack of towels T and to perform other functions. The shelf 22 is substantially horizontal and is arranged above the bottom 14 in spaced adjacent relation thereto.

It is preferred to removably support the shelf 22 in the case 10. In the arrangement illustrated in the drawings two transversely or horizontally spaced sets of opposed indented parts 24 are provided on the bottom 14 and the shelf 22 and screws 25 are passed through openings in the parts 24. The parts 24 are indented to receive the heads and the nuts of the screws 25 and to 65 form bosses about the screws. Tubular spacers 23 are arranged on the screws 25 between the opposed indented parts 24 to support or to assist in supporting the shelf 22. An upturned flange 27 extends along the forward edge of the case bottom 14 and may assist in supporting the shelf 22. The flange 27 may be in substantially the same vertical plane as the forward edges of the case sides 13 and the shelf 22 projects forwardly beyond the flange 27. The forward edge 70 of the shelf 22 is in substantially vertical align-

ment with the case front F, that is, the forward edge of the shelf 22 has a central portion in the plane of the front wall portion 17 and has rearwardly and laterally divergent edge portions in the planes of the diverging wall portions 18 of 5 the front F. A rearwardly-turned bead 28 may extend along the forward edge of the shelf 22 to make the edge round and smooth.

In accordance with the invention the lower edge of the case front F is spaced above the shelf 10 22 to leave a substantially horizontal slot which forms the towel outlet opening 29 of the case 10. The lower edge of the central wall portion 17 is horizontal and therefore substantially parallel with the shelf 22 and is in close proximity 15 to the shelf. The lower edges of the divergent wall portions 18 slope upwardly and rearwardly from the central wall portion 17 so that the side parts of the outlet opening 29 are of increased height. Notches 30 may be provided in the lower 20 edges of the wall portions 18 adjacent the flanges 19 and similar notches 31 may be provided in the divergent edge portions of the shelf 22 to facilitate the grasping of the folded portions of the towel T as will be more fully described. 25

The case 10 further includes an inclined guide and support member 32 arranged above the forward portion of the shelf 22. The member 32 may be substantially T-shaped in plan view to have a central portion 32a extending rearwardly 30 from adjacent the forward central edge of the shelf 22 and a transverse head portion 32b joining the portion 32a and extending laterally in opposite directions therefrom to have its opposite ends adjacent the case sides 13. The member 32 slopes upwardly and rearwardly from its forward edge and is substantially flat. Suitable lugs 33 on the central portion 32a of the member 32 are riveted or otherwise fixed to the shelf 22 to assist in securing the member in place. 40 Tabs on the rear edge of the portion 32b are rolled into tubes 34 and these tubes are spaced apart and are located adjacent the case sides 13. Pins 35 are passed inwardly through openings in the case sides 13 and extend through the tubes 45 34 to assist in supporting the member 32. A rotatable roll 36 extends between the tubes 34 and has longitudinal openings 37 in its opposite ends. The pins 35 extend into the openings 37 to rotatably support the roll 36. The roll 36 has a 50 substantially horizontal axis of rotation extending transversely through the case 10 a substantial distance forwardly from the back 12a. The roll 36 projects or extends above the upper plane of the member 32a so that the lowermost towel 55 T of the supply stack rests upon it as illustrated in Fig. 6 of the drawings. It will be observed that the member 32 is shaped to leave two substantially triangular spaces 38 above the shelf 22 and directly inward from the divergent edges of 60 the shelf. The member 32 assists in supporting the stack of towels T, in guiding the ejecting elements and in guiding the towels T to the outlet opening 29 as will be more fully described.

The towels T are in the form of separate or 65 individual sheets of paper toweling initially of rectangular configuration. The two forward corner portions 40 of the towels T are folded back upon the bodies of the towels along diagonal lines of folding X. This makes the towels T of non-regular hexagonal shape. The angle of the lines of folding X of the corner portions 40 is the same as that of the divergent wall portions 18 of the case front F. In order to render the stack of towels T more compact and to facilitate the 70 75

vertical stacking of the towels, the rear portions of the towels T are folded back upon the bodies of the towels to constitute rear folds 41. The rear folds 41 are preferably folded upon the same sides of the towel bodies as the forward corner portions 40. The towels T are stacked one upon the other in the same relative positions and with their folded corner portions 40 and their folds 41 at their lower sides.

10 The stack of towels T is arranged in the case 10 so that the lowermost towel T rests on the roll 36 and the member 32. The roll 36 is the highest towel supporting element of the device and therefore assumes a major portion of the 15 weight of the stack. The roll 36 is freely rotatable and forms an antifriction towel supporting element that materially reduces the frictional resistance offered to withdrawal of the lowermost towel T from the stack. The towels T are hung 20 or draped on the roll 36 in such a manner that the lowermost towel T slopes downwardly and forwardly from the roll 36 and rests flatly on the inclined member 32 and the rear parts of the lowermost towel slope downwardly and rearwardly 25 toward the case back 12a. The folded corner portions 40 of the lowermost towel T are directly above the openings or spaces 38 and are partially unsupported. Because of this arrangement the forward folded corner portions 40 of the lower- 30 most level T may project from the body of the towel.

Means is provided to support the rear portion of the stack of towels T in such a manner that the rear fold 41 of the lowermost towel T may 35 hang free to engage with the roll 36 when the said towel is withdrawn. In the preferred construction illustrated in the drawings the shelf 22 has a rear part 42 turned upwardly and then forwardly. The rear edge portion of the lower- 40 most towel T, that is, the portion of the lowermost towel adjacent the line of folding of its rear fold 41, rests upon the shelf part 42. Thus the part 42 serves to support the rear portion of the 45 stack of towels T and allows the rear fold 41 of the lowermost towel to hang free as illustrated in Fig. 6 of the drawings. It will be observed that the towels T contained in the case 10 are very difficult of access through the opening 29.

The ejecting means 11 is operable by the means 50 12 to cooperate with the forward folded parts of the lowermost towel T to advance said towel to a position where its said folds 40 are conveniently accessible at the front F of the case 10. The ejecting means 11 operates to bodily move 55 the lowermost towel T to bring its two folded or doubled corner portions to projected position where they are convenient for engagement by the user. The means 11 includes what I will term an ejector 43 shiftable or reciprocable on the shelf 22. The ejector 43 may be a flat generally rectangular member and is preferably shiftable on the upper side of the shelf 22. When the ejector 43 is in its normal position its rear edge is at the shelf part 42 and its forward portion is below the rear portion of the member 32. The ejector 43 is provided with openings 44 that 60 make the screws 25 accessible when the parts are in the normal positions. The forward portion 43a of the ejector 43 slopes upwardly and forwardly. Two substantially horizontal tabs 46 extend forwardly from the inclined portion 43a. The tabs 46 extend from the forward edge of the inclined portion 43a and are therefore elevated 65 above the body of the ejector 43. The elevated

tabs 46 are adjacent the sides 13 of the case 10. Each tab 46 has two spaced depending fingers 47.

The ejector 43 is guided for substantially horizontal movement in the case 10. A forwardly and rearwardly extending slot 48 is provided in the shelf 22 and a guide 49 is attached to the under side of the ejector 43 to operate in the slot 48. The opposite edges of the guide 49 have sliding cooperation with the side walls of the slot 48 to effectively guide the ejector 43. Lugs 50 project downwardly from the opposite ends of the guide 49 and protrude from the lower side of the shelf 22. The lugs 50 extend laterally beyond the opposite sides of the slot 48 having shoulders 51 cooperable with the under side of the shelf 22 15 to prevent upward movement of the ejector 43. Bumpers 52 of rubber or the like are provided on the lugs 50. Depending tongues 53 are provided at the opposite ends of the slot 48. The bumpers 52 are cooperable with the tongues 53 20 to limit the movement of the ejector 43.

The ejecting means 11 further includes towel engaging elements 54 on the ejector 43. An element 54 is pivotally supported between each pair of fingers 47. Pivot pins or rods 55 extend 25 through openings in the fingers 47 and similar fingers 56 on the elements 54 and pivotally support the elements between the fingers 47. The elements 54 project forwardly from below the horizontal elevated tabs 46 of the ejector 43 and 30 their forward parts are cooperable with the doubled or folded forward corner portions of the lowermost towel T. The elements 54 are shaped to effectively engage these folded portions of the lowermost towel T to bodily move the said towel. 35 Each element 54 has a forward edge 57 parallel with the planes of the front wall portions 18 and parallel with the lines of folding X of the towels T and forward edges 58 extend rearwardly and laterally in diverging relation to the edges 57. 40 The edges 57 and 58 join at rounded points 59.

The towel engaging elements 54 are movable forwardly in the spaces 38 and are automatically controlled or governed to feed the doubled forward portions of the lowermost towel T downwardly and outwardly through the outlet opening 29. Spring means are provided for yieldingly urging the elements 54 to positions where their forward parts slope upwardly and forwardly as 45 illustrated in Figs. 4 and 5 of the drawings. These 50 means may comprise leaf springs 60 attached to the elements 54 and bearing upwardly against the under sides of the inclined portions 43a of the ejector 43. The elements 54 are provided with tails which constitute cams 61. The cams 61 extend 55 downwardly and rearwardly from the elements 54 when the same are in their normal positions. Openings 62 are provided in the shelf 22 to receive and cooperate with the cams 61. The forward walls 62a of the openings 62 are 60 turned or curved downwardly and are rounded to be engaged by the cams 61 as will subsequently be described.

When the ejector 43 is in its retracted or normal position the front parts of the elements 54 65 have their upper sides in cooperation with the forward edges of the portion 32b and the cams 61 project into the rear parts of the openings 62. The points 59 of the elements 54 are normally adjacent the forward edges of the portion 32b 70 and may be engaged by the under side of the lowermost towel T. During forward movement of the ejector 43 the points 59 are held in engagement with the under side of the lowermost towel T by the action of the springs 60 so that pas- 75

sage of the elements between the towel and its forward folds 40 is assured. When the edges 57 and the points 59 approach or come into cooperation with the lines of folding X the cams 61 5 come into engagement with the walls 62a and this cooperation causes the elements 54 to pivot downwardly as they advance forwardly. The cooperation of the forwardly and downwardly moving elements 54 with the towel T at or adjacent 10 its lines of folding X bodily moves the lowermost towel forwardly and directs its doubled forward corners downwardly and outwardly through the outlet opening 29 to be readily grasped in front of the cabinet at the divergent front wall portions 18. In practice the elements 54 move downwardly and forwardly in the spaces 38 substantially in parallelism with the inclined member 32.

In accordance with the invention yielding abutments are provided on the shelf 22 to be engaged by the towel folds 40 during forward movement or ejection of the lowermost towel T to maintain the folds in their bent-back or folded condition. Leaf springs 64 are secured to the upper side of the shelf 22 adjacent the divergent forward edges of the shelf to hold the folds 40 of the lowermost towel T in engagement with the under sides of the elements 54. The springs 64 serve to prevent unfolding or straightening 30 out of the folds 40 when the same are being acted upon by the ejecting elements 54 and, if desired, may serve to normally support the folds 40 adjacent their lines of folding.

The means 12 for operating the ejecting means 35 11 is operable to shift or reciprocate the ejector 43. The means 12 is characterized by its simplicity. In accordance with the invention the means 12 comprises a pivoted lever 65 operatively connected with the ejector 43 and projecting from the case 10 to be manually operated. The lever 65 is arranged in the space 40 between the bottom 14 and the shelf 22 and projects outwardly through a slot 66 in a side 13 of the case. A suitable handle or button 67 is 45 provided on the protruding part of the lever 65 to facilitate its operation. In the simple preferred structure illustrated one of the screws 25 serves to pivotally support the lever 65. An opening 67 is provided in the lever 65 and receives the 50 spacer 26 on the said screw 25 so that the screw serves to pivotally carry the lever. The indented parts 24 serve as bearings to prevent vertical rocking of the lever.

The operative connection between the lever 65 55 and the ejector 43 includes a longitudinal slot 68 in the inner portion of the lever and a pin 69 on the ejector cooperating with the slot. The pin 69 may be fixed to the guide 49 of the ejector to project from its under side. A head 60 69a is provided on the pin 69 and has an annular peripheral groove 69b. The slot 68 is provided at its outer end with an enlargement 68a adapted to receive the head 69a of the pin 69 so that the groove 69b may cooperate with the parts 65 of the lever 65 bordering the slot 68. It is believed that it will be understood how the head 69a of the pin 69 may be introduced in the enlargement 68a so that the groove 69b may slidably cooperate with the parts of the lever 65 bordering the slot 68. An extensible spring or tension spring 70 is connected between the lever 65 and a lug 71 on the shelf 22 to automatically return the lever and the ejector 43 and to normally hold the ejecting means retracted. A rearward force applied to the knob 67 pivots the le-

ver 65 to produce a forward movement of the ejector 43. When the force or pressure is removed from the button 67 the spring 70 returns the ejector 43 and the lever 65 to their normal position. It will be noted that the ejector 43 5 together with its elements 54 and the shelf 22 together with the member 32 form a unit which may be inserted in the case 10 as a single structure.

Assuming that the case 10 contains a stack of 10 towels T as illustrated in the drawings, a user may readily obtain a towel by merely pressing rearwardly on the button 67 of the lever 65. This actuation of the lever 65 produces forward movement of the ejector 43 and its towel T engaging 15 elements 54. The elements 54 may have their points 59 in engagement with the under side of the lowermost towel and the points remain in engagement with the towel as the ejector moves forwardly. When the edges 57 of the elements 20 54 engage or approach the lines of folding X the cams 61 come into engagement with the walls 62a and cause the elements 54 to pivot downwardly. Thus the elements 54 have a compound movement, moving downwardly as well as forwardly. This movement of the elements 54 while in engagement with the lines of folding X moves the lowermost towel T forwardly and ejects its doubled forward corner portions downwardly and outwardly through the outlet opening 29. 30 The springs 64 hold the folds 40 up against the under sides of the elements 54 and assure the desired forward movement of the lowermost towel T by the ejector elements 54.

When the ejector 43 has reached the end of 35 its forward stroke the manual pressure may be removed from the lever button 67 to allow the spring 70 to return the ejector 43 to its original position. The doubled forward corner portions of the lowermost towel T may then be readily 40 grasped at the front F adjacent its divergent wall portions 18 and a forward pull on these portions of the towel will withdraw the towel from the case 10. During the withdrawal of the lowermost towel T its rear fold 41 comes into engagement 45 with the roll 36 and the roll effectively unfolds or straightens out the rear fold 41 as the towel movement continues. Thus a complete unfolded towel is obtained by the user of the cabinet.

It is to be particularly noted that the ejecting 50 means 11 operates to advance the lowermost towel T to a position where its forward corner portions of double thickness may be grasped by the user for the purpose of withdrawing the towel. These portions of the towel T being of 55 double thickness have sufficient strength to withstand the forward pulling force applied by the user and do not fail or tear even though the user's hands may be wet when he engages them.

Having described only a typical preferred form 60 and application of my invention I do not wish to be limited or restricted to the specific details herein set forth, but wish to reserve to myself any variations or modifications that may appear to those skilled in the art or fall within the scope 65 of the following claims.

Having described my invention, I claim:

1. A device for dispensing paper sheets each having at least one portion folded back upon itself, the device including a case having a discharge opening at its forward portion, means for supporting a stack of the towels in the case with their folded-back portions at their under sides, an ejector in the case, means supporting the ejector for movement toward and away from 75

the opening, an element pivotally carried on the forward end of the ejector to move therewith and having a part engageable in the fold of the lowermost sheet of the stack to move the lowermost sheet, and a part fixed in the case cooperating with the element to pivot the element downwardly relative to the ejector during movement of the ejector toward said opening so that said part of the element moves the said folded-back portion 10 of the sheet downwardly and forwardly to a position where its folded-back portion protrudes from the opening whereby the said sheet has a part of double thickness accessible to the user.

2. A device for dispensing paper sheets each having at least one portion folded back upon itself, the device including a case having a discharge opening, means for supporting a stack of the sheets in the case with their folded-back portions at their under sides, an ejector in the case, means supporting the ejector for movement toward and away from the opening, the ejector including a shifttable element operable to engage in the fold of the lowermost sheet of the stack to move the lowermost sheet, an upwardly facing abutment in the case adjacent the opening, means for shifting the element downwardly during movement of the ejector toward the opening so that the element directs the forward part of the lowermost sheet through the opening and moves it down against said abutment whereby the latter maintains the said portion in its folded-back condition, and means for operating the ejector.

3. A device for dispensing paper sheets each having a portion folded back against its inner side, said device comprising a case for holding a supply of said sheets and having a discharge opening, means for supporting a stack of sheets in the case with the forward portion of the lowermost sheet adjacent and sloping downwardly and forwardly toward said opening with its folded-back portion free, an ejecting element, means mounting the element in the case for movement toward said opening to engage in the fold of the lowermost sheet including a carrier for moving the element horizontally and a pivotal connection between the element and the carrier, and a part in the case cooperating with the element to direct it downwardly as it moves forwardly whereby the element moves the lowermost sheet to a position where its folded-back portion and the sheet portion thereabove are accessible for grasping by the user, and means for operating the carrier.

4. A device for dispensing paper sheets each having a forward portion folded back upon its under side and a rear portion folded back upon its under side, the device including a case having a discharge opening, means for supporting a stack 60 of the sheets in the case, an ejecting element in the case movable toward the opening to come into engagement with the lowermost sheet and move its forward portion through the opening for grasping by the user whereby the lowermost sheet 65 may be withdrawn from the case, the said means including, a stack supporting part located in the case to enter the rear fold of the lowermost sheet as the sheet is withdrawn from the case to direct the rear fold bodily downward to flex mainly at the line of fold so the rear portion of the sheet 70 is unfolded as it is withdrawn from the case, and means for operating the ejecting element.

5. A device for dispensing paper sheets each having a forward portion folded back on its under side, the device including a case having a dis-

charge opening, means for supporting a stack of sheets in the case with the forward parts of the lowermost sheet sloping downwardly and forwardly toward the opening free of support for the outer part of the folded-back portion, a carrier in the case shifttable forwardly, an ejecting element movable with the carrier and engageable with the fold formed by the folded-back portion of the lowermost sheet, means normally holding the element in an up position to engage the lowermost sheet, means for moving the element downwardly as the carrier moves forwardly whereby the element moves the lowermost sheet to a position where its doubled-back forward parts protrude from the opening for grasping by the user, and means for moving the carrier.

6. A device for dispensing paper sheets each having a forward portion folded back on its under side, the device including a case having a discharge opening, means for supporting a stack 20 of sheets in the case with the forward parts of the lowermost sheet sloping downwardly and forwardly toward the opening, a carrier in the case shifttable forwardly, an ejecting element pivotally supported on the carrier to move therewith and engageable in the fold formed by folded-back portion of the lowermost sheet to move the sheet, means for pivoting the element downwardly during forward movement of the carrier whereby the element moves downwardly and forwardly to 30 move the lowermost sheet to a position where its forward part of double thickness is accessible to the user, and means for moving the carrier.

7. A device for dispensing paper sheets each having a forward portion folded back on its under side, the device including a case having a discharge opening, means for supporting a stack of sheets in the case with the forward parts of the lowermost sheet sloping downwardly and forwardly toward the opening, a carrier in the 40 case shifttable forwardly, an ejecting element pivotally supported on the carrier to move therewith and engageable in the fold formed by the folded back portion of the lowermost sheet to move the said sheet, means for pivoting the element downwardly during forward movement of the carrier whereby the element moves downwardly and forwardly to move the lowermost sheet to a position where its forward part of 45 double thickness is accessible to the user, the last 50 mentioned means including cam parts on the element and case cooperating during said movement of the carrier, and means for moving the carrier.

8. A device for dispensing paper sheets each having a forward portion folded back upon its under side and a rear portion folded back upon its under side, the device including a case having a discharge opening, means for supporting a stack of the sheets in the case comprising a rotatable roll engaged by the lowermost sheet along 60 a line transverse thereof and spaced between its front and rear edges whereby the forward portions of the sheets hang downwardly and forwardly and the rear portions of the sheets hang downwardly and rearwardly, an ejector in the 65 case below the roll, means supporting the ejector for movement toward the opening, a part on the ejector cooperable with the lowermost sheet at its forward folded portion to move the same downwardly and outwardly through the opening, 70 said roll being located to engage in the fold formed by the said rear folded portion of the lowermost sheet to unfold said rear folded portion during the forward movement of the lowermost sheet; and means for moving the ejector.

9. A device for dispensing paper sheets each having a forward portion folded back on its under side, the device including a case having a discharge opening, means for supporting a stack of sheets in the case with the forward parts of the lowermost sheet sloping downwardly and forwardly toward the opening, a carrier in the case shiftable forwardly, an ejecting element movable with the carrier and engageable in the fold of the lowermost sheet portion, means for directing the element downwardly and forwardly as the

carrier moves forwardly whereby the element moves the lowermost sheet to a position where its doubled-back forward parts protrude from the opening for grasping by the user, a spring carried in the case located to engage and yieldingly hold the folded-back portion of the said sheet in the folded condition as the sheet moves forwardly and downwardly to retain said portion in its folded-back condition. 5
